UNITED STATES PATENT OFFICE

1,972,003

WATER TUBE BOILER

Walter S. Almy, Providence, and Charles F. H. Almy, Edgewood, R. I., assignors to Almy Water Tube Boiler Company, Providence, R. I., a corporation of Rhode Island

Application March 14, 1933, Serial No. 660,630

7 Claims. (Cl. 122—359)

This invention relates to a boiler and has for one of its objects the compact arrangement of the heat transfer surfaces of the water tubes of a boiler.

5 Another object of the invention is the arrangement of the water tubes whereby an economical operation may be had and an increased circulation and steaming provided in the boiler.

Another object of the invention is the provision 10 of the arrangement of the tubes such that they may be easily accessible for cleaning purposes.

Another object of the invention is the provision of an arrangement which will be quiet in starting by reason of the increased circulation.

15 Another object of the invention is the provision of a balanced arrangement with substantially equal portion of heating surface on either side of the boiler that uniform circulation about the boiler may be provided.

20 Another object of the invention is the provision of tubes of such diameter and of such shape that a maximum amount of heat may be absorbed and a maximum lifting action had on the water contained within the tubes.

25 A still further object of the invention is the provision of a box-shaped base drum to afford better circulation and heating in the boiler.

With these and other objects in view, the invention consists of certain novel features of 30 construction, as will be more fully described, and particularly pointed out in the appended claims.

In the accompanying drawings:

Fig. 1 is a sectional view through substantially 35 the center of the boiler looking from the front toward the rear thereof on line 1—1 of Fig. 2.

Fig. 2 is a central section on substantially line 2—2 of Fig. 1.

Fig. 3 is a section on line 3—3 of Fig. 1.

40 Fig. 4 is a section on line 4—4 of Fig. 1.

Fig. 5 is a perspective view illustrating the arrangement of the tubes of the boiler.

Fig. 6 is a view similar to Fig. 1 illustrating a down draft instead of an updraft boiler as 45 shown in Fig. 1.

Fig. 7 is a perspective view of a modified form of base drum to which the lower ends of the tubes are connected.

It is desirable in the use of water tube boilers 50 to provide a maximum amount of heating surface in a compact area which shall be consistent with a certain desired circulation of the water through the tubes from the base drum to the steam header, and in order that this may be accomplished in a fountain type water tube boiler

we have so arranged the water tubes that they may be positioned one close to the other by which substantially walls of tubes are provided on three sides and over the top of the combustion chamber, and we have so arranged these tubes that a balanced action is provided in that the circulation along each side of the boiler is substantially the same, and the following is a detailed description of the present embodiment of this invention illustrating the preferred means by which these advantageous results may be accomplished.

With reference to the drawings, 10 designates a base drum which we have shown as of generally U shape, there being provided a connecting portion 11 and legs 12 extending therefrom. Each of these legs is provided with a removable cap 13 which may be removed for cleaning purposes. The connecting portion 11 is provided with an inlet conduit 14 which will be connected to the return line from the apparatus to which steam is supplied by the boiler. This base drum 10 is suitably supported in a frame work 15 by the ends of the arms extending through the framework as at 16, and the inlet conduit 14 extending through the framework as at 17, thus suitably supporting the base drum spaced from the floor or support for the boiler.

At the upper end of the boiler we provide a steam header 18 consisting of a suitable water 85 and steam compartment having outlet openings 19 and 20 for supplying steam to a house or other apparatus or equipment to which the boiler is connected. Extending through this steam header, as shown in Fig. 1, is a smokestack or combustion gas conduit 21 for the passage of flue gases therethrough.

The base drum and steam header are connected by a series of water tubes which provide for the circulation of the water about the combustion chamber. These tubes are arranged in compact relation as will be seen from Fig. 4 and substantially form vertical walls about three sides of the combustion chamber which chamber we will designate generally as 25.

The water tubes are arranged in what we conveniently term sets, each consisting of two tubes 26 and 27 extending from opposite legs 12 of the base drum and arranged in a single vertical plane extending laterally of, and at right angles, to the legs 12 of the base drum. The tube 26, as shown in Figs. 1 and 5, extends vertically a substantial distance and then is bent as at 28 to extend horizontally as at 29 then reversely bent as at 30 to extend in the opposite direction along a hori-

110

zontal path as at 31, thence again bent as at 32 to extend vertically as at 33 through the bottom 34 of the header 18 to a point above the water level. Over the end of this tube there is a deflector or baffle 35 to throw downwardly any water ejected from the tube by the steam formed in the tube and rising therein. The other pipe of the set opposite the tube 26 lies in the same plane therewith vertical to, and at right angles to the parallel legs 12. This tube 27 extends vertically upwardly from the leg 12, is bent as at 36 to extend horizontally as at 37, is then bent reversely as at 38 to again extend in the opposite direction horizontally as at 39, and then is bent as at 40 to extend vertically upwardly as at 41 through the wall 34 of the steam header to a point above the water line. Over the end of this pipe there is also located the baffle 35 as before mentioned.

As will be observed from Fig. 5 the bends 36, 38 and 40 and the horizontal portions 37 and 39 formed by these bends are located above the level of the horizontal portions 29 and 31 of the pipe 26; and the arrangement is such that the reverse bends 39 and 38 each approach closely the vertical rising portions of the tubes 26 and 27 but extend just short thereof by which arrangement we are able to compactly arrange a set of a pair of tubes in a single plane with several sets of such tubes 26 and 27 close together. In fact the distance between the centers of the tubes of adjacent sets is such that another tube of the same diameter could not be inserted between them.

Adjacent sets, however, are alternately arranged, that is the tubes 26 and 27 are placed in the reverse relation whereby if the tube 26 is on the right hand side of one set it will be on the left hand side of the next set, whereby we will retain our horizontal portions in a balanced arrangement and tubes on the opposite side of the boiler will be alternately first contacted by the combusted gases, and by providing these sets in reverse order we obtain a symmetrical arrangement throughout the entire length of the boiler.

These sets of tubes 26 and 27 are the up-flow tubes and as they extend above the normal water level in the header 18 no down-flow will be had through them. In order, however, that a down-flow may be had we connect a series of back tubes 42 to extend just through the wall 34 and connecting the steam header with the base drum 10 so that a circulation may be obtained downwardly through these pipes to the base drum 10 and upwardly through the up-flow pipes 26 and 27 to the header. All of these tubes, as will be apparent from the sectional views of Figs. 3 and 4 are positioned closely together and form substantially a wall on three sides of the combustion chamber, the front side 43 being left open for the position of an oil burner therein or if desired a grate may be supported and a coal fire had in this combustion chamber.

The heat will be partially transferred from the combustion chamber to the vertical portions of the tubes about this combustion chamber and as the gas rises the heat will be transferred through the horizontal portions of the tubes 29 and 31 first and 37 and 39 secondarily after which these gases will contact and pass through the steam header giving up some of their heat to this part of the furnace and thence pass outwardly to the flue.

Continuous circulation is obtained through these water tubes and by reason of their single horizontal loop greater circulation is obtained than were the tubes zig-zagged back and forth

several times. Further, by reason of the tube extending horizontally across just short of its cooperating tube in the same plane two tubes, or a so-called set, may be formed in a single vertical plane, and a far more compact arrangement of the tubes is had than were the horizontal portion to extend slightly further into the path of the vertical portion of the other tube in the set, and thus require it to be staggered to one side or the other of the vertical plane thereof.

The tubes are preferably welded to the base drum and header and thus securely held in place, and it will be apparent that other forms of headers and bases may be used, and we have illustrated one other form of base consisting of a shallow box construction 50 to which there is a top plate 51 welded, and into which container these series of tubes 26, 27 and 42 may be welded as above pointed out.

The combustion chamber is completed by a casting or wall extending about and enclosing the circulation pipes which wall is designated as 52 at the sides, 53 at the rear, and 54 at the front, wall 54 being provided with suitable doors 56, peephole 57 or other desirable openings for boiler construction.

In Fig. 6 we have illustrated a down-draft boiler in which the tubes 26 and 27 are substantially inverted, and the combustion chamber arranged at 58 with the draft taking a downward path 105 across the horizontal portions of the tubes and out through the flue opening 59. In this instance the longer straight portion of the tubes extends up into the steam header 18 but the flue 21 extending through the steam header is absent, however otherwise the construction is similar to the arrangement shown in Fig. 1 more fully above described.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. In a boiler, a base drum, a steam header, generally parallel vertical rows of tubes connecting said drum and header with opposite tubes in substantially the same plane at right angles to the plane of the rows of tubes, the tubes of one row in each plane having portions extending horizontally across into close adjacency to the opposite tubes in the other row of said plane with the horizontal portions of opposite tubes staggered one with reference to the other, and with the horizontal portions of the tubes in adjacent planes oppositely arranged and also similarly staggered.

2. In a boiler, a base drum, a steam header, sets of tubes connecting said drum and header, each set comprising a pair of tubes in a single plane with each tube generally vertically arranged and having portions extending horizontally across toward the vertical portion of the other tube of the pair with the portions from one side above or below the portions of the other side, adjacent sets being oppositely arranged and alternate sets alike and said horizontal portions maintained in the same relation to each other.

3. In a boiler, a base drum, a steam header, sets of tubes connecting said drum and header, each set comprising a pair of tubes in a single plane with each tube generally vertically arranged and having portions extending horizontally across

- toward the vertical portion of the other tube of the pair with the portion from one side above or below the portion from the other side, said sets being in close parallel vertical relation adjacent 5 sets being oppositely arranged and said horizontal portions maintained in the same relation to each other.
4. In a boiler, a base drum, a steam header, sets of tubes connecting said drum and header, 10 each set comprising a pair of tubes in a single plane with each tube generally vertically arranged and having portions extending horizontally across toward the other tube of the pair, one tube of each set having its horizontal portion at a different 15 level than the horizontal portion of the other tube of the set and adjacent sets being oppositely arranged and said horizontal portions maintained in the same relation to each other.
5. In a boiler, a base drum, a steam header, sets of tubes connecting said drum and header, each 20 set comprising a pair of tubes in a single plane with each tube generally vertically arranged and having portions extending horizontally across toward the other tube of the pair, one tube of each set having its horizontal portion at a different level than the horizontal portion of the other tube of the set, and said sets being alternately arranged.
6. In a boiler, a base drum, a steam header, sets of tubes connecting said drum and header, each 25 set comprising a pair of tubes in a single plane with each tube generally vertically arranged and having portions extending horizontally across toward the other tube of the pair, one tube of each set having its horizontal portion at a different level than the horizontal portion of the other tube of the set, and said sets being alternately arranged.
7. In a boiler, a base drum, a steam header, sets of tubes connecting said drum and header, each 30 set having a right and a left hand generally vertical tube in a single plane, the right hand tube of each set having a portion extending horizontally towards and in close proximity to the left hand tube and the left hand tube having a portion extending horizontally towards and in close proximity to the right hand tube, said horizontal portions being one above the other in each set, one set having the horizontal portion from the right hand tube below the horizontal portion from the left hand tube and the next set having the horizontal portion from the left hand tube below the horizontal portion from the right hand tube, the lower horizontal portions all being at substantially the same horizontal level and the upper horizontal portions all being at substantially the same horizontal level.
